(57) CLAIM

The ornamental design for a metal stud, as shown and described.

DESCRIPTION

FIG. 1 is a perspective view of a metal stud showing my new design which is of indeterminate length;

FIG. 2 is a side elevational view thereof;

FIG. 3 is a top plan view thereof, the bottom being identical;

FIG. 4 is a opposite side elevational view thereof; and,

FIG. 5 is a front side elevational view thereof, the rear view being identical.
